UNITED STATES PATENT OFFICE.

EDWIN F. HULBERT, OF KENOSHA, WISCONSIN, ASSIGNOR OF ONE-HALF
TO L. C. BROOKS, OF KENOSHA, WISCONSIN.

BOX-FASTENER.

No. 825,463.

Specification of Letters Patent.

Patented July 10, 1906.

Application filed July 25, 1905. Serial No. 271,140.

To all whom it may concern:

Be it known that I, EDWIN F. HULBERT, a citizen of the United States, residing at Kenosha, in the county of Kenosha and State of Wisconsin, have invented certain new and useful Improvements in Box-Fasteners, of which the following is a specification.

This invention comprises a novel form of lock or fastening means particularly designed for boxes, crates, and receptacles or in like capacity.

The intent of the invention is to secure a lock of very simple construction and yet possessed of great substantiality necessary in the actual use thereof.

For a full description of the invention and the merits thereof and also to acquire a knowledge of the details of construction of the means for effecting the result reference is to be had to the following description and accompanying drawings, in which—

Figure 1 is a perspective view showing the side and top portions of a crate, partially broken away, the invention applied thereto.

Fig. 2 is a vertical section on the line X X of Fig. 4. Fig. 3 is a vertical section on the line Y Y of Fig. 4. Fig. 4 is a horizontal section on the line Z Z of Fig. 2. Fig. 5 is a view similar to Fig. 2, embodying a modification.

Corresponding and like parts are referred to in the following description and indicated in all the views of the drawings by the same reference characters.

The invention is shown in the construction wherein it is particularly adapted for use on receptacles, portions of a box being illustrated in the drawings in showing the application of the invention.

The numeral 1 designates a side of a crate or receptacle, and the numeral 2 the cover. A fixed catch 3 in the form of a pin or stud is secured to the cover 2 and is to be engaged by suitable means applied to the side 1 in order to positively lock the cover 2 from movement. The catch 3 is formed with a beveled nose and a notch 4, so that it will readily engage with a latch-plate 5. An attaching-plate 6, which is secured in any substantial manner, preferably by screws, to the interior of the side 1 of the receptacle, is formed at its upper portion with an oblong integral extension or enlargement 7, having a vertical opening 8 therethrough, said opening being adapted to receive the stud or fixed

catch 3 as the cover is closed down upon the side 1 in closing the receptacle. The latch-plate 5 is pivoted at one end to the under side of the extension or enlargement 7, and the opposite end of said latch-plate is formed with an opening receiving a projection 9 at its inner extremity of a push-rod 10, movable in a horizontal opening 11 in the side 1. The push-rod 10 is thus pivotally connected with the latch-plate and passes through an opening in the plate 6 also and is provided at its extremity with a finger-piece or button 12, which is actuated in order to force the rod 10 inwardly and impart pivotal movement to the latch-plate 5 to disengage the latter from the catch 3. An integral lug 13 projects from the outside of the plate 6 beneath the enlargement 7 and spaced from the latter, and the latch-plate 5 is pivotally movable between the parts 7 and 13 snugly fitting therebetween, as shown most clearly in the drawings. The lug 13 is formed with a vertical opening 14 in alinement with the opening 8 of the enlargement 7, and this opening receives the head or outer end of the catch 3 when the latter is in engagement with the latch-plate 5. The latch-plate 5 is provided with a recess 15 leading from an edge thereof and located about centrally of its ends, the innermost side of the recess being beveled downwardly and extending about half-way across and arranged in the path of movement of the catch or stud 3 as the latter is forced through the opening 8 in the enlargement 7. Between the button or finger-piece 12 of the rod 10 and the outer side of the plate 6 is a coil-spring 16, which is mounted upon the rod 10 and which normally tends to expand and force the rod to the outer limit of its movement. The normal tendency of the spring 16 is such as to hold the latch-plate 5 against the plate 6 and will cause said latch-plate to automatically engage with the catch 3 as the latter is forced into the openings 8 and 14 in closing the cover 2.

In actual use when the cover 2 closes down upon the side 1 the catch 3 enters the opening 8 and pushes the plate 5 to one side against the tension of the spring 16 until the recessed portion of said plate engages in the notch 4 of said catch, whereupon the plate positively engaging the end of the catch 3 locks the catch from displacement. To open the re-

ceptacle, it is necessary to push inwardly upon the button or finger-piece 12, and thereby disengage the plate 5 from the catch 3, permitting withdrawal of the catch 3 upon opening of the cover 2 in a manner which will be obvious.

Fig. 5 embodies a modification of the invention in which the under side of the enlargement 7 is provided with a recess 17, in which is seated a coil-spring 18. The spring 18 bears at one end against an end of the recess 17, and the opposite end of said spring engages or bears against a projection 19, extending upwardly from an end of the latch-plate 5 adjacent the point of connection of the push-rod 10 therewith. In this instance the spring 18 coacts with the latch-plate to cause the same to automatically engage with the catch 3 as the latter enters the opening 8 in the enlargement 7, and the spring 16, used in the construction shown in the preferred forms of the invention, will be disposed of when the modification is utilized.

Having thus described the invention, what is claimed as new is—

1. In combination, a receptacle embodying a side and a cover, an attaching-plate secured to the side and arranged upon the interior of the receptacle, said plate having an extension projecting from the attaching-plate and provided with a vertical opening therein, a lug projecting from the attaching-plate in spaced relation to the extension, a latch-plate pivoted at one end to the under side of the extension and arranged for movement between the extension and the lug, a

catch applied to the cover and adapted to engage the latch-plate by entering the opening in the extension of the attaching-plate, a horizontally-arranged pressure-rod passing through the attaching-plate and the side of the receptacle and having its inner end connected with the latch-plate at the end opposite that pivoted to the extension, and a spring arranged to coact with the latch-plate to normally hold the same in engagement with the catch on the cover.

2. In combination, a receptacle embodying a side and a cover, an attaching-plate secured to the side and arranged upon the interior of the receptacle, said plate having an extension projecting therefrom and provided with an opening therein, a catch applied to the cover and adapted to enter the opening in the extension of the attaching-plate, a latch-plate pivoted at one side of the extension and arranged to engage the catch aforesaid, a pressure-rod passing through the aforesaid side of the receptacle and through the plate and connected at its inner end with the latch-plate, a finger-piece applied to the outer end of said pressure-rod, and a coil-spring arranged upon the pressure-rod and bearing at one end against the finger-piece thereof to normally hold the latch-plate in engagement with the catch of the cover.

In testimony whereof I affix my signature in presence of two witnesses.

EDWIN F. HULBERT. [L. s.]
